Primary Examiner — Paula Greene(74) *Attorney, Agent, or Firm* — Coastal Patent Agency;
Joshua Schoonover(57) **CLAIM**I claim the ornamental design for ear can headphone, as
shown and described.**DESCRIPTION**

FIG. 1 is a front perspective view of ear can headphone showing my new design with two identical ear pieces, each respective ear piece of the ear can headphone resembles a soft drink can;

FIG. 2 is a rear perspective view of one ear piece of the ear can headphone shown separately for ease of illustration;

FIG. 3 is a front perspective view of the ear piece thereof;

FIG. 4 is a side view of the ear piece with an inner ear insulator represented by dashed lines thereof;

FIG. 5 is a side view of the ear piece without the inner-ear insulator thereof;

FIG. 6 is a rear view of the ear piece thereof;

FIG. 7 is a top view of the ear piece thereof;

FIG. 8 is a bottom view of the ear piece thereof;

FIG. 9 is a front view of the ear piece without the inner ear insulator thereof; and,

FIG. 10 is a front view of the ear piece with dashed lines representing the inner ear insulator as unclaimed subject matter thereof.

The broken lines form no part of the design.
